ORGAN CONSOLE

Laurens Hammond, Chicago, Ill., assignor to
 Hammond Instrument Company, Chicago, Ill.,
 a corporation of Delaware

Application October 28, 1949, Serial No. 124,138

5 Claims. (Cl. 84—424)

1

My invention relates generally to electric organs, and more particularly to consoles for instruments of this type.

In the manufacture of organ consoles it has been nearly universal and standard practice to have two or more manuals of 61 keys each, with the keys for the same pitch in alignment, and to use a pedal clavier of 32 or 25 pedals. I have discovered that this time honored practice is inefficient and have devised a console which can be produced at a substantially lower cost than the standard console without sacrificing any of its functional utility in the rendition of most kinds of musical compositions but instead, substantially increasing the facility with which the instrument may be played. The invention resides primarily in the concept that by combining various parts of electric organ consoles in a peculiar and unique combination and arrangement the number and cost of parts conventionally used could be greatly reduced without detracting in any way from the main functions of the instrument as a whole, but on the contrary, in many respects increasing its versatility and usefulness.

As indicated by the reduced length of the upper manual of the electric organ shown in my prior Patent Number 1,956,350, I have long felt that the conventional organ console could be changed to decrease its cost without substantial sacrifice in the utility of the instrument. The simplification proposed in said patent did not achieve popular approval probably because in that instrument I merely omitted some of the keys of one manual together with their functions, and did not make any provision for having other parts perform the excised functions. Since that time all organs commercially produced have, to the best of my knowledge, incorporated at least one manual having 61 keys, and in a large majority of instruments, two manuals each of at least 61 keys. The pedal claviers in most commercial organs included at least twenty-five and often the standard thirty-two pedals.

By approaching the problem of the design of an organ console and associated parts from the functional and utilitarian point of view, and disregarding in many respects the conventional standards, I have been able to produce an electric organ at a cost in the order of one-half as much as would be required for the production of an organ having a conventional console, and this has been done without placing any material limitations upon the manner of playing the instrument, or in its performance in the rendi-

2

tion of nearly all organ selections. Thus for example, I have found that many keys of both manuals are used so infrequently in the rendition of organ selections that such keys are substantially useless, and can very well be eliminated. This is of course because the player conventionally plays the melody on the upper manual with the right hand and plays the accompaniment on the lower manual with his left hand.

10 This is a natural and comfortable position of the hands in playing the instrument. Since the melody is, generally speaking, at least an octave higher in pitch than the notes of the accompaniment, it will be seen that the elimination of 15 certain keys does not in any way place limitations upon the usefulness of the two manuals in the rendition of nearly all musical compositions. Furthermore, I have found that compensation may be made for the elimination of many keys by displacing the manuals laterally.

Another conventional feature of organ console construction which adds materially to its cost and also adds to the difficulty of playing, without materially improving the musical versatility of 25 the instrument, is the provision of a full 32 pedal clavier. It is seldom that the organist plays chords by depressing two pedals of the pedal clavier and the reason that so many pedals have been used in the past is that the tones of the 30 organ, particularly the electric organ, have a short decay period and the organist must therefore depress the pedals in rapid succession to obtain a sustained bass accompaniment. Thus in conventional organs the organist must at times 35 use both feet in depressing the pedals so that the pedals may be played in a legato manner. I have found that twelve pedals in the pedal clavier are fully adequate for the playing of the bass 40 accompaniment tones required in the rendition of organ music if the pedals and the mechanisms operated or controlled thereby are of such character that the tone produced as a result of depression of one pedal will continue to sound for a long time after the pedal is released or until 45 another pedal is depressed.

It is therefore the primary object of my invention to provide a greatly simplified electric organ which can be manufactured at greatly reduced cost, and which is more easily played than 50 organs of conventional construction.

Other objects will appear from the following description, reference being had to the accompanying drawings in which:

Figure 1 is a perspective view of the improved 55 console; and

Figure 2 is an enlarged perspective view of various control elements which form part of the console.

The console comprises a case 10 which houses the electrical tone signal generating means, preferably of the type shown in said Patent No. 1,956,350, as well as the output and amplification circuits which supply the tone signals to a speaker 12 preferably mounted behind the fall board 14 which forms part of the case 10.

The upper manual 16 and the lower manual 18 each have forty-four keys 20, extending from F₁ (87.307 C. P. S.) to C₆ (1046.502 C. P. S.).

The quality of the tones produced upon depression of keys of the upper manual is controlled by a group A of drawbars 21 to 29 which respectively control the amplitude of the fundamental, 3rd, 2nd, 4th, 6th, 8th, 10th, 12th and 16th harmonic partials. In a similar manner the quality of the tones produced upon depression of keys of the lower manual is controlled by a group B of drawbars 31 to 38 which respectively control the amplitude of the fundamental, 2nd, 3rd, 4th, 5th, 6th, 8th, and the combined 10th and 12th harmonic partials. Each of the drawbars may be manually adjusted to any one of eight different positions to select any of eight different degrees of intensity of the partial in the composite or synthesized tone produced upon depression of the keys 20 of the associated manual.

A similar drawbar 39 is provided to control the intensity of the bass tones produced under the control of a pedal clavier 40 comprising twelve pedals 42 for the bass note C0 (32.703 C. P. S.) to B0 (61.735 C. P. S.). This pedal clavier may be of the construction shown and claimed in Patent No 2,499,244, granted February 28, 1950.

The generators for the pedal-controlled bass tones preferably produce tone signals of complex quality and have their outputs controlled by latching switches and an intensity envelope controlling vacuum tube in the manner more fully disclosed and claimed in the copending application of John M. Hanert, Serial No. 111,742 filed August 22, 1949, and in Patent No. 2,480,132, granted August 30, 1949.

The console also includes six tilttable two-position control tablets 44 to 49 mounted in suitable openings formed in an insulating plate 53. These tablets determine various characteristics of the tonal output of the instrument. For example, tablet 44 controls the volume or intensity of the pedal controlled tones relative to the tones controlled by the manuals, that is whether the pedal tones shall be "normal" or "soft." Tablet 45 may be used to determine whether the pedal tone intensity envelopes shall have an attack which is "normal" or "slow," while tablet 46 may be used to determine whether the decay of the pedal tones shall be "normal" or "fast." Tablet 47 may be used to control the vibrato, whether "on" or "off." The vibrato apparatus is preferably of the type shown in the patent to John M. Hanert No. 2,382,413, and tablet 48 may be used to determine whether the vibrato shall be "normal" or shall be a "vibrato chorus," that is a mixture of the vibrato frequency modulated output signal with the unmodulated signal. The amount of the vibrato effect may be controlled by tablet 49, that is, whether it shall be "normal" or "small."

The overall volume of the instrument is controlled by an expression pedal 50 mounted for pivotal movement in the customary manner and extending through an opening 52 in the fall board 14. A sustaining control element 54 is mounted for transverse sliding movement on the expres-

sion pedal 50, being positioned that it may be operated easily by the player's foot while it is in position for operation of the swell pedal.

In conventional electric organs it is usually desirable to include means for introducing the effect of reverberation, as by the apparatus disclosed in my prior Patent No. 2,230,836 dated February 4, 1941. This was due to the fact that electric organs are frequently played in rooms having a short reverberation time. By having the pedal controlled bass tones decay at a relatively slow rate, the effect of reverberation is attained. It is sufficient if only the bass tones decay slowly, since this is the effect the listener associates with hearing organ music in large church auditoriums, where the higher treble range frequencies are attenuated so rapidly that they do not contribute materially to the reverberation effect. Thus the use of the "normal" decay under the control of tablet 46 results in the practical equivalent of acoustical reverberation, making it unnecessary to provide complicated and costly reverberation effect apparatus of the kind shown in said Patent 2,230,836.

If, as is usual, the drawbar 21 is adjusted to a position other than "O" or "off," and the drawbars 23 to 29 are adjusted to positions such that the tone frequencies controlled by the latter do not mask the tone frequencies controlled by the drawbar 21, the resultant complex tones produced, as keys 20 of the upper manual are played, will be of the same pitch as the complex tones produced by playing keys 20 of the lower manual which are displaced one octave to the left. Thus the pitch ranges of the tones controlled by the upper and lower manuals are identical and the console may be considered as comprising two manuals, each of the same 3½ octave pitch range (3 octaves plus 8 notes), with the lower manual shifted to the left a distance corresponding to one octave of keys.

By virtue of the fact that the lower manual is displaced to the left of the upper manual, and because custom and convenience dictate that the left hand usually be used for playing the accompaniment on the lower manual while the right hand is used to play the melody on the upper manual, the playing of the instrument is greatly facilitated. The organist finds that he does not have to cross his right hand over the left hand nearly as often, nor to as great an extent as he would on a conventional console. In playing the overwhelming majority of musical selections on the improved console, the player finds that his hands are in natural positions, that is his right hand is to the right of the left hand, and usually his hands are on their respective sides of the center of the console. (The key C₂ of the upper manual and key C₃ of the lower manual are at the center of the console.)

The convenience to the player of the particular arrangement of the upper and lower manuals is enhanced by virtue of the fact that the left hand is generally used to play the accompaniment and the pitch of the accompaniment notes is most often within the range represented by the lowest two octaves of keys of the lower manual. Thus the player's left hand is nearly always directly in front of his left shoulder and the player is not required to swing his forearm laterally to any great extent in playing the usual accompaniment chords. Likewise the upper manual is so positioned that the center of the melody range of the majority of compositions is approximately in front of the right shoulder of the player so that in playing the majority of musical selec-

tions the player will be required to move his forearm about equally to the right and left of the median naturally convenient position.

Since the cost of an organ is in considerable measure determined by the cost of the console case, it is desirable to reduce its size as much as possible without detracting from its usefulness and from the convenience with which it may be played. The height of the console disclosed herein may be substantially less than that of a conventional console, that is the distance from the lower manual to the floor may be reduced substantially from two to three inches. The width of the console is also much less than that of the conventional console. This is made possible partly because of the reduction in the number of pedals of the pedal clavier and the placing of the pedals closer to the center of the instrument. If the pedals 42 of the pedal clavier were placed in their conventional positions they would have to be placed somewhat to the left of the positions in which they are shown, and the player would therefore be inconvenienced by moving his foot somewhat further to the left in depressing the lowest pedal. As the pedal clavier is located in the improved console, the left foot of the player naturally is positioned at about the center of the pedal clavier.

The pedals 42 lie close to the floor so that in playing them the heel of the left foot just grazes the floor while the pedals are depressed with the toe or ball of the foot. In conventional pedal claviers, due to the former desirability of making it possible for the player to "heel and toe," (that is, depress pedals in succession alternately with the heel and toe so as to render the base accompaniment continuous by the legato effect thus obtained) it was necessary that the natural pedals extend from the console a sufficient distance to enable the player to depress them with his heel. Thus the top surface of the white or natural pedals were usually several inches from the floor level. By using the shorter pedals and having the tones sustained after the pedal has been released the "heel and toe" technique is unnecessary in playing the instrument and therefore the natural position of the heel may be at floor level instead of several inches above the floor level as in conventional consoles. The bench may therefore be made lower and as a result the player's knees are in lower positions and therefore the manuals may be correspondingly lowered. The height of the console is thus reduced by several inches. As previously described, the width of the console is also reduced, thereby substantially reducing the cost of the instrument as well as making it more generally useful because it is more acceptable for use in small rooms of apartments and homes. The reduction in weight due to the decrease in size is also a substantial advantage, making the instrument more easily portable and reducing packing and freight costs.

In conventional consoles having 25 or 30 pedals it is necessary to extend the pedal clavier to the full width of the instrument and as a result it is necessary to locate the swell or expression pedal above the levels of the pedals of the pedal clavier. The right foot used to operate the expression pedal is therefore in a somewhat uncomfortable, inconvenient and unnatural position. By virtue of using the short one octave range pedal clavier in my improved console the expression pedal 50 may be lowered about five inches so as to be nearly at floor level. This is

a further reason why the height of the console may be reduced. The expression pedal 50 is located to the right of the center line of the instrument, approximately the same distance that the center of the pedal clavier is located to the left of the center line of the console, and these distances are such that the player sitting at the center of the instrument may operate the various pedals with the feet in natural positions, in which greatest muscular relaxation is possible.

Since the player is never required to use his right foot for the depression of any of the pedals of the pedal clavier he may at all times rest it upon the expression pedal, and since his left foot is required to move at the most throughout an octave range the physical energy required for the playing of the instrument is substantially reduced.

Since the tone signal generating system and the output system do not form part of the present invention they are not disclosed herein. They may be of any well known construction. For example, the generating system may be of the type shown in said Patent No. 1,956,350, to which reference may also be had for a disclosure of the key operated switching and drawbar controlled circuits. Said application Serial No. 111,742, and Patents Nos. 2,480,132 and 2,357,191 disclose examples of tone signal generating and switching means for control by the pedal clavier. However the tone generating means may be of a variety of types, and may include reeds, pipes or other non-electrical musical tone generators.

While I have shown and described a particular embodiment of my invention, it will be apparent to those skilled in the art that numerous modifications and variations may be made in the form and construction thereof, without departing from the more fundamental principles of the invention. I therefore desire, by the following claims, to include within the scope of my invention all such similar and modified forms of the apparatus disclosed, by which substantially the results of the invention may be obtained by substantially the same or equivalent means.

I claim:

1. In a two manual organ, having an upper and a lower manual of substantially the same length and range of musical pitches, a console case supporting the lower manual in such position that the keys of said lower manual are positioned one whole octave to the left of the corresponding keys of said upper manual.

2. In an organ having means for producing tones of the musical scale, a console including means for controlling the production of the tones comprising an upper manual and a lower manual, the manuals having substantially the same number of keys extending over not more than four octaves and controlling production of the substantially same range of musical tones, the keys of the lower manual being positioned one full octave to the left of the keys of the upper manual which control the production of tones of corresponding pitch.

3. An organ console comprising similar upper and lower manuals of forty-four keys each for controlling the production of tones of the same pitch compass, the lower manual being positioned to the left of the upper manual a distance corresponding to one octave of keys.

4. In a two manual and pedal organ having an upper and a lower manual of substantially the same length and musical pitch range, a console case supporting the lower manual in such position

that the keys of the lower manual are located one whole octave to the left of the corresponding keys of the upper manual, a pedal clavier to be played by the left foot of the player, the clavier comprising an octave of short pedals having their playing surfaces located sufficiently close to the floor that the player may rest his heel on the floor while easily depressing the pedals, the pedal clavier being located to the left of the center of the console, and an expression pedal located close to the floor and to the right of the center of the console for convenient operation by the right foot of the player.

5. For use in a two manual and pedal organ of the type in which the tones controlled by the pedals continue to be produced for a substantial time after the pedal has been released or until

10 a pedal calling for a tone of different pitch is depressed, a console comprising, an upper manual and a lower manual, said manuals having substantially the same number of keys for controlling the production of tones of substantially the same pitch range, a case supporting the manuals in position such that the keys of the lower manual are located the distance of one full octave of keys to the left of the corresponding keys of the upper manuals, and a pedal clavier of substantially one octave range and comprising short pedals positioned so close to the floor that they may be depressed with the toe while the heel is resting on the floor.

LAURENS HAMMOND.
